UNITED STATES PATENT OFFICE.

FRANK F. LOOMIS, OF AKRON, OHIO.

DYNAMO-ELECTRIC MACHINE.

SPECIFICATION forming part of Letters Patent No. 395,157, dated December 25, 1888.

Application filed October 30, 1886. Serial No. 217,549. (No model.)

To all whom it may concern:

Be it known that I, FRANK F. LOOMIS, a citizen of the United States, and a resident of the city of Akron, in the county of Summit and 5 State of Ohio, have invented a new and useful Improvement in Dynamo-Electric Machines and Commutators, of which the following is a specification.

The objects of my invention are to reduce 10 the number of parts and simplify the construction of the machine; to secure the effect of two compound-wound field-magnets by the use of a yoke wound with fine insulated wire connecting field-magnets wound with coarse 15 insulated wire; to facilitate the winding of the armature-spools and enable them severally to be readily removed and replaced for repairs or other purposes; to provide a commutator simple in construction, perfectly insulated, and readily connected with the armature-wires, and, generally, to connect the several parts with the least use of bolts, rivets, or screws.

My invention consists in the devices illustrated in the accompanying drawings, as hereinafter described and claimed.

The accompanying drawings show, respectively, in Figure 1, one of the armature-rods, which constitutes a spool-core, unwound; Fig. 2, the same with center spirally wound; Fig. 3, an end elevation of Fig. 2; Figs. 4 and 5, side and end elevations, respectively, of a complete armature-spool; Fig. 6, a side elevation of the armature-shaft and ends, showing the manner of retaining the spools; Figs. 7 and 8, the inner and outer faces, respectively, of the armature ends; Fig. 9, a section of Fig. 7 at the line $\alpha\alpha$; Fig. 10, an elevation of a complete machine, excepting the commutator, and the left field-magnet unwound; Fig. 11, a side elevation, enlarged, of commutator; and Figs. 12, 13, 14, 15, and 16, details of the commutator on the same scale.

Referring to the drawings substantially in 45 their order, the armature-spools each consist of a soft-iron core, A, Fig. 1, with its central part of less diameter than the ends, and having its ends deeply recessed by longitudinal notches. The central part of said core is then 50 wound with soft uninsulated iron wire, a, until of equal diameter with the ends, the object

of which is to add surface to the core. The whole is then wound longitudinally through the end notches with insulated wire, B.

Upon the armature-shaft C are two collars, 55 D D', from each of which project radial arms d d', which are attached to and support the annular disks E E', the outer faces of which are plain, their inner faces being provided with a series of cells, e, for the reception of 60 the ends of the cores A.

The ends of the cores A enter the cells e in each disk, and the disks are caused to approach each other and be retained by the nuts c on the shaft C, as shown in Fig. 5, in 65 which two unwound cores are shown.

The armature thus constructed is mounted in bearings f on the base F, which also supports the field-magnets G, each having a semi-circular face concentric with the armature 70 and provided with a spool, g, wound with coarse insulated wire. Connecting the outer ends of the field-magnets G is a bar or yoke, H, the central part of which is also wound with a coil of fine insulated wire, h.

Upon one end of the shaft C is mounted the commutator I, which consists of a hollow cylinder, J, Fig. 16, of glass or other non-conducting material, on the periphery of which are placed lengthwise a series of bars, i, each 80 provided with a binding-post and having their outer faces cut away at each end, leaving thin projecting ends.

A hard-rubber ring, j, with a radial flange, fits upon the thin ends of the bars i, with the 85 flange against the thicker shoulder. Upon the ring j is forced a metallic hoop, L, Fig. 12, which binds the ends of the bars firmly on the cylinder J, and is retained by the nuts l on the shaft C. The bars i are insulated 90 from each other by a thin strip of non-conducting material, preferably mica. (Not shown in the drawings.)

The bars i correspond in number with the armature-spools, and each is connected by 95 means of its binding-post with the inner end of the insulated coil of one spool and the outer end of the coil of its adjacent spool.

The letter I' indicates one of the commutator-brushes, which is secured to a post, K', 100 connecting with the positive end of the line by means of a wire, k', and L' the other com-

mutator-brush, which is secured to a post, M' , connected with one terminal of the coil g at the right of the machine by a wire, l' , the other terminal of said coil connecting by 5 means of a wire, n' , with one terminal of the coil g at the left of the machine, the other terminal of said coil connecting with the negative end of the line by a wire, p' . The terminals of the coil h of fine wire connect, 10 respectively, with the positive end of the line by a wire, r' , and with the post M' , carrying the brush L' , by means of a wire, s' , the current during the operation of the machine taking the direction shown by the arrows. 15 This construction enables me to wind each spool before it is placed in position and to disconnect it quickly and remove and replace it when necessary. By the use of the coil h on the yoke H , I secure for each field-magnet 20 G the effect of a compound-wound magnet and reduce the size of the machine.

I claim—

1. An armature for dynamo-electric generators, consisting of a number of spools, each 25 having an iron center spirally wound with iron wire and longitudinally wound through recesses in its ends with insulated wire, mounted by devices, such substantially as shown, about a central shaft, substantially as 30 and for the purpose hereinbefore set forth.
2. In an armature for dynamo-electric generators, the combination, with a number of electro-magnets, of two annular disks mount-

ed on a central shaft, having recesses in their adjacent faces in which the ends of said magnets rest, and screw-threaded nuts by which they are retained on said central shaft, substantially as shown, and for the purpose specified. 35

3. The combination, in an electric generator, 40 of two electric field-magnets, $g g$, wound with coarse-wire series coils, the yoke H , wound with fine-wire shunt-coils, the brushes I' and L' and their supporting-posts, and the conductors P' , n' , l' , and s' , connecting the respective coils, the commutator I , and the rotating armature-spools B , the whole arranged to operate substantially as specified. 45

4. A commutator for dynamo-electric machines, consisting of a non-conducting cylinder, J , a series of conducting-bars, i , each provided with a binding-post and insulated from each other by intermediate insulating material, the bars projecting beyond the ends of the cylinder and having their projecting 50 ends cut away, the hard-rubber rings j , and the metallic hoops L , whereby the bars are bound firmly upon the cylinder, substantially as specified. 55

In testimony that I claim the foregoing I have hereunto set my hand this 24th day of September, A. D. 1886.

FRANK F. LOOMIS.
